UNITED STATES PATENT OFFICE.

FOIRE RICCIARDELLI, OF JERSEY CITY, NEW JERSEY, AND JACOB B. BLEICHRODE, OF BROOKLYN, NEW YORK, ASSIGNORS TO CRYSTAL PERCOLATOR COMPANY, INC., OF NEW YORK, N. Y., A CORPORATION OF NEW YORK.

DESIGN FOR A PERCOLATOR.

47,545.

Specification for Design.

Patented July 6, 1915.

Application filed May 5, 1915. Serial No. 26,159. Term of patent 7 years.

To all whom it may concern:

Be it known that we, FIORE RICCIARDELLI and JACOB B. BLEICHRODE, citizens of United States, residing at Jersey City and Brooklyn, respectively, in the counties of Hudson and Kings, respectively, and States of New Jersey and New York, respectively, have invented a new, original, and ornamental Design for Percolators, of which the following is a specification, reference being had to the accompanying drawing forming a part thereof.

The drawing is a perspective view showing a percolator of this design.

We claim—

The ornamental design for a percolator as shown.

FIORE RICCIARDELLI.
JACOB B. BLEICHRODE.
